UNITED STATES PATENT OFFICE.

CHARLES E. BUELL, OF NEW HAVEN, CONNECTICUT, ASSIGNOR OF TWO-THIRDS TO JAMES G. SMITH, OF HACKENSACK, NEW JERSEY, AND GEORGE W. COY, OF MILFORD, CONNECTICUT.

TELEPHONE-EXCHANGE APPARATUS.

SPECIFICATION forming part of Letters Patent No. 248,138, dated October 11, 1881.

Application filed June 15, 1881. (No model.)

To all whom it may concern:

Be it known that I, CHARLES E. BUELL, a citizen of the United States, and a resident of New Haven, in the county of New Haven and State of Connecticut, have invented certain new and useful Improvements in Telephone-Exchange Apparatus, of which the following is a specification.

My invention constitutes an improvement upon that class of telephone-exchange apparatus in which the connection and disconnection of the subscribers' lines with one another are effected from the subscribers' stations and without the assistance of central-office attendants.

Although I have shown in the accompanying drawings one particular form of automatic switch for the purpose of illustration, my invention is applicable to any automatic exchange apparatus.

As hitherto constructed, automatic switch apparatus has been defective in that it has been impossible for direct communication to be held, telephonically or otherwise, between the central office and subscribers over the wires used in operating the switch and in communicating between subscribers, while, further, in case of accident to the switch or derangement thereof, the business of the exchange 30 would for the time being come to a stand-still.

The object of my invention is to remedy these defects and to provide means whereby, without disturbing the automatic switch, oral communication may be held between the central office and any subscriber, or vice versa, while, further, in case of derangement of any portion or all of the automatic switch devices, communication may still be held between subscribers.

To this end my invention consists in interposing between the automatic switch and the subscribers' lines a manually-operated telephone-exchange switch of any ordinary construction, the various subscribers' circuits passing through said switch to the automatic switch, means being also provided for connecting the various lines to ground before passing to the automatic switch and for disconnecting

or breaking the connection to ground through the latter.

I have shown in the accompanying drawings, Figures 1 and 2, two forms of manually-operated switch and two ways of carrying out my invention. Other switch-boards and other means or devices for making the various electrical connections contemplated by me may, however, be substituted for those shown without departing from the spirit of the invention.

Referring to Fig. 1 of the drawings, A represents a section of an automatic switch constructed after the manner set forth in Letters Patent of the United States granted M. D. and T. A. Connolly and T. J. McTighe, December 9, 1879, No. 222,458, before referred to, wire 6 of the subscribers' wires being shown as connected thereto.

The various subscribers' circuits are numbered from 1 to 6, consecutively, and each passes to the automatic switch and its earth-connections through a manually-operated telephone switch-board, C, interposed between the automatic switch A and the various lines. Entering the central office, each circuit is, through an annunciator and call-bell, a, to a key on switch, b, adapted to disconnect the line from the switch-board and connect it to a calling battery or generator, c; to a spring-jack, d, of any approved construction, to be used in connection with divided insulated metallic tips e', e, connected to telephone communicating apparatus, M; to a vertical strip, e, of the switch-board; to a switch, f, and thence to the controlling devices of the automatic switch, and to earth. Line 6 is shown connected to a subscriber's station at B, at which point the apparatus is of substantially the construction indicated in the patent to Connolly and McTighe, S representing the switch adapted to connect the line either to a rheotome, B, and a pole-changer, O, for battery P, to a call-bell, R, or to a telephone, T. Said switch also closes the circuit of battery P through the electrodes and the primary of the induction-coil in M T at the same time that it connects the line to the telephone-receiver T.

The switches f in switch apparatus C are each

adapted to break the circuit of a subscriber's line with the automatic switch apparatus and its ground and connect the line to earth through a wire, *g*.

5 The normal operation of the system when the various subscribers' circuits pass to the switch apparatus A is the same as the patent above referred to, and need not be rehearsed. Should, however, oral communication be desired between the central office and a subscriber, or vice versa, the switch-board apparatus C may be instantly brought into use, the predetermined signal necessary to make such a desire on the part of a subscriber known being given 15 on the bell *a* by the opening and closing of the battery *P* by means of switch *S* or other device, while, vice versa, the central-office attendant depresses key *b*, thus placing battery or generator *c* to line and simultaneously disconnecting the line from the automatic and the manual switch devices, so as to prevent the battery *c* from affecting the electro-magnetic devices of switch A.

Telephone apparatus M may be inserted into 25 the line by means of the spring-jacks *d* and tips *e*. The necessity for such communication may arise from a failure of the automatic switch device to operate properly, so as to place a subscriber in communication with the party desired, in which case he can communicate to the 30 central-office attendant the fact that he fails to get a response, and the attendant thereupon makes the desired connection in switch-board C, before doing which he disconnects the 35 switches *f* from the points to which are connected the wires leading to the automatic switch A.

Should the automatic switch become so far derailed as to require repair and make its further use for the time being impossible, it and its earth-connections may be entirely disconnected from the subscribers' wires by means of the switches *f*, and the ground-connection *g* substituted. The lines may then be connected 45 and the business of the exchange continued without interruption by means of the switch C alone, its operation in this duty being well understood. Other contingencies may arise under which it may be brought either wholly or 50 partially into use in conjunction with or wholly independent of switch A; but I do not deem it necessary to specify them all.

In Fig. 2 of drawings I have shown a somewhat different form of manual switch-board, although the general operation of the apparatus is substantially the same as that of Fig. 1. Instead of the switches *f* normally interposed in the circuit and adapted to be turned, so as to substitute a ground-connection, *g*, I employ an 60 upper row of switches, *t*, whose pivots are con-

nected to ground *g*, and a series of connecting-plugs, *x*, one in each circuit.

Switches *t* may be turned so as to connect with the line-strips *e*, thus connecting the lines to ground, while the connection of the various 65 circuits with the automatic switch A is controlled by the plug-switches X.

Instead of connecting-strips *m*, as shown in Fig. 1, switch-levers *n* are used for connecting the lines. The operation of these devices is well 70 understood.

In Fig. 2, line 1 is shown connected to the subscriber's station B and to the automatic switch A. Another form of pole-changer, G, is here shown. The effect of turning its arm 75 11 12 so as to occupy the position shown in full and dotted lines and connect with the segments H can be readily followed by tracing the circuits. The switch S connects the line to rheotome, bell, and telephone in the manner 80 indicated, (also shown in Fig. 1;) but the circuit of the battery through the transmitter is controlled by a gravity-switch, G S, in a well-known manner.

Other forms of manual central-office switch 85 may be substituted for those shown by interposing them in the circuits in substantially the same manner.

What I claim as my invention is—

1. The combination, with an automatic telephone-exchange switch, of a manual exchange-switch interposed in the subscribers' circuits between the lines and the automatic switch, substantially as described.

2. The combination of an automatic telephone-switch, a manual exchange-switch interposed in the subscribers' circuits between the lines and the automatic switch, and devices adapted to break the connection of the lines with the automatic switch and to substitute an 95 independent ground-connection for the manual switch.

3. The combination, substantially as described, of an automatic telephone-exchange switch and a manual exchange-switch interposed between the automatic switch and the lines, and signaling-keys adapted to make connection with a generator and to simultaneously break connection with the automatic switch devices, substantially as described.

4. The combination, substantially as described, of an automatic telephone-exchange switch, a manual exchange-switch, and a disconnecting-switch interposed between the two and adapted to close an independent connection to earth.

CHARLES E. BUELL.
